UNITED STATES PATENT OFFICE.

JOHN C. BURNELL, OF CINCINNATI, OHIO, AND JOHN MEYER, OF COVINGTON, KENTUCKY.

DESIGN FOR A SIGN.

SPECIFICATION forming part of Design No. 16,734, dated June 15, 1886.

Application filed October 10, 1885. Serial No. 179,519. Term of patent 7 years.

To all whom it may concern:

Be it known that we, JOHN C. BURNELL and JOHN MEYER, the former of Cincinnati, in the county of Hamilton and State of Ohio, 5 and the latter of Covington, Kenton county, Kentucky, have invented a new and useful Design for a Sign; and we do hereby declare the following to be a full, clear, and exact description of said invention, reference being had to 10 the accompanying drawings, and to the letters or figures of reference marked thereon, which form a part of this specification.

Figure 1 is a front view of our newly-designed sign. Fig. 2 is an end view of the same 15 sign.

Our new sign is intended to represent the one-half of a keg or cask, and its appearance is that of the outside of a keg or cask in longitudinal half-section, and is in alto-rilievo, 20 so as not only to represent but to configure the one-half of a keg or cask in half-section, as aforesaid.

In the drawings, *a a* represent the staves,

and *b b* the hoops, and *c* the half of the head of the keg in imitation of the half of a keg or cask. The two ends of the sign are alike, and Fig. 2 is a representation of each end. The parts above described, which are in alto-rilievo and represent the half of a keg, are affixed at the line of apparent sectional division of the 30 keg to a plane base, *d*.

What we claim as new, and desire to secure by Letters Patent, is—

The design for a sign herein shown and described, consisting of a configuration and representation in alto-rilievo of the longitudinal half-section of a keg or cask having staves *a a*, two series of hoops, *b b*, and half-heads *c*, all affixed to a plane base or background, *d*. 35

In testimony whereof we affix our signatures 40 in presence of two witnesses.

JNO. C. BURNELL.
JOHN MEYER.
